UNITED STATES PATENT OFFICE

FRIEDRICH WILHELM HAACK, OF BERLIN, GERMANY

PENCIL WITH LEAD SHIFTABLE AND FIXABLE BY A SLIDING SLEEVE

Application filed May 26, 1930. Serial No. 455,937.

This invention relates to a pencil with a lead shiftable and fixable by a slideable sleeve. These pencils consist of a case with longitudinal slot, in which the lead is situated and fastened on an arm projecting from the longitudinal slot. This arm terminates in a slideable sleeve, surrounding the case, which enables the lead to be shifted from the outer side. The object of the invention is to secure 10 the slideable sleeve in any desired position.

For this purpose round keys are known, which project from a square hole of the rotatable ring encircling the slideable sleeve. Other constructions show instead of the 15 square hole a groove in the rotatable ring, which on being turned is pushed over the key and thereby clamps the sleeve with the arm engaging laterally through the longitudinal slot of the pencil and carrying the lead. In 20 these devices the key is soon pressed flat and worn down, besides which the square hole or groove soon widens so that often, after being used a certain time, the slideable sleeve is no longer clamped with the lead moved thereby.

25 This objection is overcome, according to the invention, in that on the sides of the slot in the pencil case clamping cheeks are provided, which are formed by bending over or the like of the flaps of the beaded band towards the 30 side on the entire length of the flaps and that the fixing ring has an eccentric groove, with which it engages over the clamping cheeks and one of which clamps against the pencil case on the ring being turned to the right or to the left.

An embodiment of the invention is illustrated by way of example in the accompanying drawing in which:

Fig. 1 shows the double sided beaded band 40 with the lead holder in perspective view.

Fig. 2 is an end view of the eccentric adjusting ring.

Fig. 3 is a section on line 3-3 of Fig. 2.

Fig. 4 shows a section on line 4-4 of Fig. 5.

Fig. 5 shows the pencil in elevation.

a is the adjusting ring on the pencil case b having a slot b'. An eccentric groove c is provided in said ring. Between the pencil case b and the adjusting ring a, a single or double sided beaded band d, e with flaps f is 50 situated in the slot d'. The edges of the flaps f are folded inwards on their whole length so that they form clamping cheeks g. The clamping cheeks g engage in the eccentric groove c of the ring a. The joint between the 55 flaps f and the clamping cheeks g is smooth on the inner side of the adjusting ring a. In the rounded portion d of the beaded band the holding band i for the lead is fitted.

By turning the adjusting ring a to the 60 right or to the left, one of the clamping cheeks g is pressed against the pencil case b so that the adjusting ring and thereby the pencil is clamped.

I claim:

65 A pencil, comprising in combination a pencil case having a longitudinal slot, a beaded band, flaps on said band folded inwards on their entire length forming clamping cheeks at the sides of said slot, and an adjusting ring 70 having an eccentric groove adapted to engage with said clamping cheeks, one of said cheeks adapted on the lateral turning of said ring to the right or to the left to clamp against said pencil case.

75 In testimony whereof I affix my signature.
FRIEDRICH WILHELM HAACK.
